UNITED STATES PATENT OFFICE.

HENRY H. ARGUE, OF DERRICK CITY, PENNSYLVANIA, ASSIGNOR OF ONE-HALF TO RICHARD W. ARGUE, OF SAME PLACE.

OIL OR ARTESIAN WELL PUMPING MECHANISM.

SPECIFICATION forming part of Letters Patent No. 380,615, dated April 3, 1888.

Application filed April 22, 1887. Serial No. 235,817. (No model.)

To all whom it may concern:

Be it known that I, HENRY H. ARGUE, a citizen of the United States, residing at Derrick City, in the county of McKean and State of Pennsylvania, have invented certain new and useful Improvements in Oil or Artesian Well Pumping Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention consists in the improvements in oil or Artesian well pumps hereinafter set forth and explained in the specification and claims, and is illustrated in the accompanying drawings, in which—

Figures 1 and 2 show a vertical section of an oil or Artesian well with my improved pumping mechanism therein, parts of the pumping mechanism being broken away so as to show the internal mechanism thereof. Fig. 3 is a vertical section of the standing valve-seat of my improved pump. Fig. 4 is a vertical section of the standing valve of the pump. Fig. 5 is a vertical section of the valve on the lower end of the pump-plunger. Fig. 6 is a vertical section of the working-barrel of my pump, showing part of the mechanism for packing the plunger in section and part thereof in elevation. Fig. 7 is a vertical section of the casing-head and the mechanism for packing the sucker-rod pipe therein. Fig. 8 is a perspective view of one of the guides used on the sucker-rod tube.

Like letters refer to like parts in all the figures.

In the construction of my improved pumping mechanism I make a working-barrel, A, from two or three feet in length, having a shoulder or collar, B, therein near the upper end thereof. Above the collar B, I cut a thread, c, to receive the end of the tubing C. The lower part of the working-barrel A, from the collar B downward, is bored out of equal size. Near the lower end of the working-barrel A, I cut a thread, a, and below this thread I bore out the lower end of the working-barrel

at D and cut a thread, d, therein to receive the section of pipe E, which connects the lower end of the working-barrel A to the standing-valve seat F, Fig. 3, the lower end of the standing-valve seat F being also provided with a thread, f, into which the perforated pipe and anchor G is secured.

In the standing-valve seat F, I place the standing valve H, Fig. 4, the outside whereof is preferably covered by a flexible ring of packing, h, which seats itself in the tapering barrel of the valve-seat F, so as to make a fluid-tight joint.

The plunger I of my pump consists of a piece of small pipe polished smooth on the outside, having secured to the lower end thereof the valve J, Fig. 5. I pack this plunger I in the barrel A by means of leather rings or sleeves L, these sleeves or rings being provided with a flange, l, on their upper ends, the edge of the flange l extending outward to the inside of the barrel A and the sleeve extending downward an inch or more on the outside of the plunger I. The first one of the sleeves is shoved up so that its flange l rests against the shoulder or collar B in the upper end of the barrel. Against the under side of the flange l, I place a metal sleeve, M, the outside whereof fits the barrel A, the lower end of said metal sleeve having an inwardly-projecting flange with an opening therein of sufficient size to admit of the passage of the plunger I. Upon the lower side of the said inwardly-projecting flange m, I form a projection, m', closely surrounding the aperture and fitting into the hole of the leather flange l below. The flange m keeps the metal sleeve central and leaves a hollow chamber within it, in which the water may act upon the tubular part of sleeve L. I then place below this metal sleeve another leather sleeve, L, and under that another metal sleeve, M, and so on until the barrel A is filled with these leather and metal sleeves L and M to near the bottom of the barrel A, where I insert under the last metal sleeve a sleeve, N, provided with a screw-thread, n, adapted to fit the thread a in the lower end of the barrel A, by means whereof the sleeve N is screwed up into the barrel A until the flanges l of the leather sleeves L and

the metal rings or sleeves M are tightly clutched between the shoulder or collar B in the upper end of the barrel A and the screw-collar N in the lower end of the barrel A.

5 In operation, the polished plunger I moves up and down through the leather sleeves L, and the weight of the fluid on the outside of the sleeves L serves to thoroughly pack the plunger and prevent the fluid from passing up 10 on the outside of the plunger. On the upper end of the plunger I, I secure sections of small pipe O, which extend upward to and out of the top of the well, where it is secured to the walking-beam P, by which it is operated, this 15 pipe O operating both as the sucker-rod and as the pipe for conveying the fluid out of the top of the well, a branch, O', being inserted into the pipe O above the casing-head for conveying the fluid away. In the upper end of 20 the working-barrel A, I secure one or more lengths of common tubing, C, which extends upward some distance from the working-barrel A, and near the upper end of said tubing I place a collar, Q, and above and below the collar Q, I place loose collars R R, which are connected together by means of strips of spring metal, S, which bow outward against the sides of the well, as illustrated in Fig. 2, which 25 springs operate to keep the upper end of the tubing central in the well. The collar Q operates to limit the movement of the loose collars R R on the tube C. In the upper end of the tubing C, I screw a collar, T, having an opening through which the pipe O will operate 30 freely, but not large enough to permit the passage of the thimbles U thereon, so that when it is desired to draw out the pipe and pump from the well the thimble U, under the collar T, will engage therewith and raise the tubing 35 C, working-barrel A, and the anchor G with it. On the pipe O, above the upper end of the tubing C, I place spiders V, Fig. 8, which operate to prevent the small pipe O from kinking and to keep it central in the well. Where 40 the pipe O passes through the casing-head W, I place a stuffing-box, X. (See Fig. 7.)

The casing-head is provided with a screw-thread, w, into which the stuffing-box X is secured by means of like screw-thread on the 45 outside thereof. This stuffing-box X is of usual and ordinary construction, and operates to prevent the gas from the well from passing up beside the pipe O, so that it is forced out through the conveyer-pipes Y Y, so as to be 50 utilized for firing the boiler, or for other purposes.

In operation my improved pump sucks the fluid through the perforated pipe G at the bot-

tom of the well and up through the standing valve H into the chamber Z, formed by the 60 pipe E, connecting the lower end of the working-barrel A with the standing-valve seat F, into which the lower end of the plunger I and the valve J extends, so that each downward stroke of the plunger I fills it with fluid and 65 forces a like amount out of the discharge-pipe O' at the top of the well.

I am aware that others have used hollow sucker-rods for pumping oil or Artesian wells, and that the same are not new; but I am not 70 aware of the use of mechanism such as I have described for operating pumps of this character. Therefore I do not broadly claim a pump having a hollow sucker-rod for pumping oil or other Artesian wells; but,

Having fully described my invention, so as to enable others to construct and use the same, what I claim as new, and desire to secure by Letters Patent of the United States, is—

1. The combination, in an oil or Artesian 80 well pump, of the working-barrel A, having a standing valve, H, and the packing-rings L M therein, substantially as shown and described, and the pipe C, secured thereto and extending upward, having thereon the fixed 85 collar Q, the loose collars R R, and curved guiding and supporting springs S, connecting said loose collars with the hollow plunger I, provided with a valve, J, and operating in said working-barrel A, and the hollow sucker-rod 90 O, having guides V thereon and operating through the stuffing-box X in the casing-head W, substantially as and for the purpose set forth.

2. The combination, in an oil or Artesian 95 well pump, of the pipe C, secured to and extending upwardly from the working-barrel A of the pump, with the thimble Q, the loose collars R R, and the curved springs S, connecting said loose collars, substantially as and 100 for the purpose set forth.

3. The combination of the pump-barrel having shoulder B, the pump-plunger I, the leather packing-sleeves L, surrounding the plunger, the clamping-nut N, and the metal sleeves M, 105 provided with flanges m and projections m', interposed between the said leathersleeves and forming hollow chambers about their lower tubular extensions, substantially as set forth.

In testimony whereof I affix my signature in 110 presence of two witnesses.

HENRY H. ARGUE.
